UNITED STATES PATENT OFFICE.

HERBERT O. SPADE AND HENRY E. SPADE, OF VICKSBURG, MICHIGAN.

OIL-FEED DEVICE.

No. 835,569.

Specification of Letters Patent.

Patented Nov. 13, 1906.

Application filed February 23, 1906. Serial No. 302,525.

To all whom it may concern.

Be it known that we, HERBERT O. SPADE and HENRY E. SPADE, citizens of the United States, residing at Vicksburg, Kalamazoo county, Michigan, have invented certain new and useful Improvements in Oil-Feed Devices, of which the following is a specification.

This invention relates to improvements in oil feed or charge delivering devices.

Our improved oil feed or charge delivering device is particularly designed for use as a lubricator, although it is very desirable for use as a liquid hydrocarbon device for explosion-engines and the like.

The objects of this invention are, first, to provide an improved feed device of the class described adapted to deliver a number of charges at the same time; second, to provide an improved feed device of the class described adapted to deliver a fixed amount at each charge; third, to provide an improved feed device of the class described in which the amount delivered is under perfect control; fourth, to provide an improved feed device of the class described adapted to accomplish the objects stated, which is very simple and economical in structure.

Further objects and objects relating to structural details will definitely appear from the detailed description to follow.

Figure 1 is an inverted view of our improved feed mechanism removed from the oil reservoir or receptacle A', the operating mechanism also being omitted. Fig. 2 is a vertical section of our improved oil-feed mechanism, the driving-gear and plungers being shown in full lines.

In the drawings similar letters of reference refer to similar parts in both views.

Referring to the drawings, A is the frame, from which is suspended the oil reservoir or receptacle A'. Arranged within the reservoir A' is a cylinder B, preferably open at each end and having a longitudinal slit B' therethrough. The cylinder B is suspended from the frame A by means of the rods B''. On opposite sides of the slit B' are outwardly-projecting perforated ears b. A bolt b' is arranged through these ears. On this bolt is a tension-spring b''. The tension of this spring is adjusted by means of the nut b''' on the bolt b'.

Arranged within the cylinder is a plunger C. The cylinder is provided with discharge ports or openings c''. These discharge-openings are connected to the parts to be lubri-

cated by the tubes or pipes C''. (See Fig. 2.) The plunger C is provided with a plurality of cylinder-like charge-pockets c, with passages c' opening thereinto. These passages are arranged to register with the discharge-passages c'' in the cylinder B when the plunger is in its upper position.

It is evident that, if desired, the cylinder B might be closed at its lower end and provided with inlet-ports adapted to register with the inlet-ports c' when the plunger is in its lower position.

The charge-pockets c are provided with plungers C'. A plunger-rod D is provided for the plunger C, the plunger being slidably mounted thereon. The plunger-rod is provided with suitable shoulders, as d d'. The plunger is frictionally fitted within the cylinder, so that it is moved with an intermittent movement. This friction can be nicely adjusted by the means we have illustrated, although other forms will readily suggest themselves to those skilled in the art to which this invention relates.

On the plunger rod D is a cross-head e, through which the pocket-plungers C' are slidably arranged. These plungers are provided with tappets e' e'', so that the plungers C are intermittently operated. The tappets e' are preferably threaded upon the plunger, so that they may be adjusted to control the movement of the pocket-plungers, thereby regulating the charge. The plunger D is connected by the rod E to the crank-wheel F', secured to the inner end of the shaft F. The shaft F is provided with suitable bearings on the frame A. On the outer end of the shaft F is a gear-wheel F'', with which the gear f is arranged to mesh. On the shaft of this gear is a pulley F'''.

In the operation of the device, the plunger C being in its lower or initial position, the plunger-rod D first acts upon the pocket-plungers C', lifting them up, and thereby opening the pockets. This draws the lubricant into the pockets through the passages c'. The shoulder d then engages the plunger C, lifting the same until the passages c' are opposite or register with the discharge-passages c'' of the cylinder B. The return movement of the plunger-rod D, engaging the tappets e'' of the pocket-plungers, forces them downwardly in the pockets and ejecting the oil therefrom through the passages c''.

The shoulder d' on the plunger then engages the plunger C, carrying it downwardly to the

end of the movement, and on the return stroke the operation is repeated. The plunger C is, as before stated, held under friction, so that it does not move until engaged by the shoulders of the plunger-rod. These shoulders are, in effect, tappets for moving the same.

We thus accomplish by a simple mechanism the opening of the pockets in the reservoir and the closing of the same opposite the discharge-passages of the cylinder. When the pockets are opened, a vacuum is created, so that they are positively filled even though the lubricant be quite heavy or thick. By adjusting the tappets e' the amount of the charge is regulated. It is evident that by this simple construction a number of bearings may be lubricated from a single apparatus.

While our improved feed device is particularly designed as a lubricator, it is, as before remarked, desirable for use as a charge device for explosion-engines and the like.

We have illustrated and described our improved feed device in detail on account of its structural simplicity, although we are aware that it is capable of considerable variation in structural details without departing from our invention.

Having thus described our invention, what we claim as new, and desire to secure by Letters Patent, is—

1. The combination of a cylinder having a longitudinal slit and delivery-passages therein there being perforated ears on said cylinder, arranged on opposite sides of said slit; a bolt arranged through said ears; a spring on said bolt for applying tension to said cylinder; a plunger having a plurality of cylinder-like charge-pockets, and passages opening into said pockets, adapted to register with the delivery-passages of said cylinder when the plunger is in one position; a plunger-rod having tappet-shoulders thereon slidably arranged through said plunger; plungers for said charge-pockets; a cross-head on said plunger-rod through which said charge-pocket plungers are slidably arranged and adjustable tappets for the said charge-pocket plungers, for the purpose specified.

2. The combination of a cylinder having a longitudinal slit and delivery-passages therein there being perforated ears on said cylinder, arranged on opposite sides of said slit; a bolt arranged through said ears; a spring on said bolt for applying tension to said cylinder; a plunger having a plurality of cylinder-like charge-pockets, and passages opening into said pockets, adapted to register with the delivery-passages of said cylinder when the plunger is on one position; a plunger-rod having tappet-shoulders thereon slidably arranged through said plunger; plungers for said charge-pockets; a cross-head on said plunger-rod through which said

60 charge-pocket plungers are slidably arranged

and tappets for the said charge-pocket plungers, for the purpose specified.

3. The combination of a cylinder having a longitudinal slit and delivery-passages therein; a spring for applying tension to said cylinder; a plunger having a plurality of cylinder-like charge-pockets, and passages opening into said pockets, adapted to register with the delivery-passages of said cylinder when the plunger is in one position; a plunger-rod having tappet-shoulders thereon slidably arranged through said plunger; plungers for said charge-pockets; a cross-head on said plunger-rod through which said charge-pocket plungers are slidably arranged; and adjustable tappets for the said charge-pocket plungers, for the purpose specified.

4. The combination of a cylinder having a longitudinal slit and delivery-passages therein; a spring for applying tension to said cylinder; a plunger having a plurality of cylinder-like charge-pockets, and passages opening into said pockets, adapted to register with the delivery-passages of said cylinder when the plunger is in one position; a plunger-rod having tappet-shoulders thereon slidably arranged through said plunger; plungers for said charge-pockets; a cross-head on said plunger-rod through which said charge-pocket plungers are slidably arranged; and tappets for the said charge-pocket plungers, for the purpose specified.

5. The combination of a cylinder having delivery-passages therein; a plunger having a plurality of cylinder-like charge-pockets, and passages opening into said pockets, adapted to register with the delivery-passages of said cylinder when the plunger is in one position; a plunger-rod having tappet-shoulders thereon arranged slidably through said plunger; plungers for said charge-pockets; a cross-head on said plunger-rod through which said charge-pocket plungers are slidably arranged; and adjustable tappets for the said charge-pocket plungers, for the purpose specified.

6. The combination of a cylinder having delivery-passages therein; a plunger having a plurality of cylinder-like charge-pockets, and passages opening into said pockets, adapted to register with the delivery-passages of said cylinder when the plunger is in one position; a plunger-rod having tappet-shoulders thereon slidably arranged through said plunger; plungers for said charge-pockets; a cross-head on said plunger-rod through which said charge-pocket plungers are slidably arranged; and tappets for the said charge-pocket plungers, for the purpose specified.

7. The combination of a cylinder having a longitudinal slit and delivery-passage therein there being perforated ears on said cylinder, arranged on opposite sides of said slit; a bolt arranged through said ears; a spring on said bolt for applying tension to said cylinder; a plunger having a cylinder-like charge-

10 pocket and a passage opening into said pocket, adapted to register with the delivery-passage of said cylinder when the plunger is in one position; a plunger-rod having tappet-shoulders thereon slidably arranged through said plunger; a plunger for said charge-pocket; an arm on said plunger-rod through which said charge-pocket plunger is slidably arranged; and an adjustable tappet for the said charge-pocket plunger, for the purpose specified.

15 8. The combination of a cylinder having a longitudinal slit and a delivery - passage therein there being perforated ears on said cylinder, arranged on opposite sides of said slit; a bolt arranged through said ears; a spring on said bolt for applying tension to said cylinder; a plunger having a cylinder-like charge-pocket and a passage opening 20 into said pocket, adapted to register with the delivery-passage of said cylinder when the plunger is in one position; a plunger-rod having tappet-shoulders thereon slidably arranged through said plunger; a plunger for 25 said charge-pocket; an arm on said plunger-rod through which said charge-pocket plunger is slidably arranged; and a tappet for the said charge-pocket plunger, for the purpose specified.

30 9. The combination of a cylinder having a longitudinal slit and a delivery - passage therein; a spring for applying tension to said cylinder; a plunger having a cylinder-like charge-pocket and a passage opening into 35 said pocket, adapted to register with the delivery - passage of said cylinder when the plunger is in one position; a plunger-rod having tappet-shoulders thereon slidably arranged through said plunger; a plunger for 40 said charge-pocket; an arm on said plunger-rod through which said charge-pocket plunger is slidably arranged; and an adjustable tappet for the said charge-pocket plunger, for the purpose specified.

45 10. The combination of a cylinder having a longitudinal slit and a delivery - passage therein; a spring for applying tension to said cylinder; a plunger having a cylinder-like charge-pocket and a passage opening into 50 said pocket, adapted to register with the delivery passage of said cylinder when the plunger is in one position; a plunger-rod having tappet-shoulders thereon slidably arranged through said plunger; a plunger for 55 said charge-pocket; an arm on said plunger-rod through which said charge-pocket plunger is slidably arranged; and a tappet for the said charge-pocket plunger, for the purpose specified.

60 11. The combination of a cylinder having a delivery-passage therein; a plunger having a cylinder-like charge-pocket and a passage opening into said pocket, adapted to register with the delivery-passage of said cylinder 65 when the plunger is in one position; a plun-

ger-rod having tappet-shoulders thereon slidably arranged through said plunger; a plunger for said charge-pocket; an arm on said plunger - rod through which said charge-pocket plunger is slidably arranged; and an 70 adjustable tappet for the said charge-pocket plunger, for the purpose specified.

12. The combination of a cylinder having a delivery-passage therein; a plunger having a cylinder-like charge-pocket and a passage 75 opening into said pocket, adapted to register with the delivery-passage of said cylinder when the plunger is in one position; a plunger-rod having tappet-shoulders thereon slidably arranged through said plunger; a plunger for said charge-pocket; an arm on said plunger - rod through which said charge-pocket plunger is slidably arranged; and a 80 tappet for the said charge-pocket plunger, for the purpose specified.

13. The combination of a cylinder having a longitudinal slit and a delivery-passage therein; a spring for applying tension to said cylinder; a plunger having a charge-pocket and a passage opening into said pocket adapt- 90 ed to register with the delivery-passage of said cylinder when the plunger is in one position; a plunger for said charge-pocket; and means for moving said plungers with a step- 95 by-step movement, for the purpose specified.

14. The combination of a cylinder having a delivery-passage therein; a plunger having a charge-pocket and a passage opening into said pocket adapted to register with the delivery-passage of said cylinder when the plunger is in one position; a plunger for said charge-pocket; and means for moving said plungers with a step-by-step movement, for 100 the purpose specified.

15. The combination of a cylinder; a movable member having a charge-pocket therein frictionally fitted in said cylinder; a plunger-rod having tappets thereon slidably arranged through said movable member; a movable member for opening and closing said charge-pocket; and means for moving the same with a step-by-step movement relative to said first-named movable member, whereby said charge - pocket is alternately opened and closed, for the purpose specified.

115 16. The combination of a cylinder; a movable member having a charge-pocket therein frictionally fitted in said cylinder; a movable member for opening and closing said charge-pocket; and means for moving said movable members with a step-by-step movement relative to each other, whereby said charge-pocket is alternately opened and closed, for the purpose specified.

125 17. The combination of a cylinder; a movable member having a charge-pocket therein; means for applying friction to said movable member; a plunger-rod having tappets thereon slidably arranged through said movable member; a movable member for opening and 130

closing said charge-pocket; and means for moving the same with a step-by-step movement relative to said first-named movable member, whereby said charge-pocket is alternately opened and closed, for the purpose specified.

18. The combination of a cylinder; a movable member having a charge-pocket therein; a plunger-rod having tappets thereon slidably arranged through said movable member; a movable member for opening and closing said charge-pocket; and means for mov-

ing the same with a step-by-step movement relative to said first-named movable member, whereby said charge-pocket is alternately opened and closed, for the purpose specified. 15

In witness whereof we have hereunto set our hands and seals in the presence of two witnesses.
